UNITED STATES PATENT OFFICE.

THOMAS SUMMERSOON, OF PARSONS, PENNSYLVANIA.

NON-REFILLABLE BOTTLE.

1,120,860.

Specification of Letters Patent. Patented Dec. 15, 1914.

Application filed March 30, 1914. Serial No. 828,350.

To all whom it may concern:

Be it known that I, THOMAS SUMMERSOON, a citizen of the United States, residing at Parsons, in the county of Luzerne and State 5 of Pennsylvania, have invented a new and useful Non-Refillable Bottle, of which the following is a specification.

The present invention appertains to non-refillable bottles, and aims to provide a novel 10 and improved device of that character.

It is the object of the present invention to provide a guard or protector within the mouth of the bottle neck, in connection with a valve disposed within the bottle neck for 15 normally closing the passage therethrough, and unique means for sealing or anchoring the guard or protector within the neck of the bottle to prevent its displacement or removal.

As a more specific object, the present 20 invention aims to provide novel means for cementing the guard or protector within the neck of the bottle.

It is also within the scope of the present 25 invention to provide a device of the nature indicated, which will be comparatively simple, non-encumbering, and inexpensive in construction, which will not be subject to corrosion, and which will be practical and 30 efficient in its use.

With the foregoing and other objects in view which will appear as the description proceeds, the invention resides in the combination and arrangement of parts and in 35 the details of construction hereinafter described and claimed, it being understood that changes in the precise embodiment of the invention herein disclosed, can be made within the scope of what is claimed, without 40 departing from the spirit of the invention.

The invention has been illustrated in its preferred embodiment in the accompanying drawing, wherein:

Figure 1 is a longitudinal section through 45 the neck of the bottle, illustrating the present invention applied thereto, the body of the bottle being broken away. Fig. 2 is a fragmental view of the bottle neck, illustrating one of the cement grooves, and 50 designating in dotted lines the position of the groove of the protector or guard. Fig. 3 is a cross section taken on the line 3—3 of Fig. 1.

In the drawings, the numeral 1 designates 55 the neck of the bottle or other vessel, the neck being provided with a conical valve

seat 2 at its lower or butt end. The bottle neck 1 is further provided with diametrically opposite longitudinal grooves or channels 3 extending from its upper or outer end, and the grooves 3 are provided at their lower or inner ends with diverging or diagonal branches 4. Each of the channels 3 with its branches 4, defines an inverted Y-shaped recess, the trunk or main portion of 60 which extends to the mouth or rim of the bottle mouth.

A tubular guard or protector 5 is disposed within the bottle neck 1 above the valve seat 2, and has its upper end protruding 70 from the neck, the lower or inner end of the tubular guard 5 being closed, as at 6, so as to prevent the insertion of implements through the neck of the bottle. The upper or protruding end of the guard 5 is 75 preferably provided with an annular bead 7, for the engagement of a "crown" seal, or the upper end of the guard 5 may normally be closed by a cork stopper 8, or its equivalent.

The lower end portion of the tubular 80 guard 5 is reduced in diameter slightly, as at 9, to provide a downwardly facing shoulder 10, a cork or similar gasket or band 11 embracing the reduced portion 9 of the guard 5 and resting against the shoulder 10. 85 The band or gasket 11 fits the interior of the bottle neck tightly, below the branches 4 of the grooves or channels 3. The reduced portion 9 is spaced from the interior walls of the bottle neck, and the guard 5 is also 90 provided with an annular groove or channel 12 directly above the shoulder 10, which intersects the branches 4 of the grooves 3. The reduced lower end portion 9 of the tubular guard 5 is provided with an annular 95 series of diagonal or oblique slots 13 extending from a point adjacent the gasket or band 11, to the lower end of the guard, to provide lateral ports for the lower or inner end of the guard leading from the annular 100 space between the reduced portion 9 and the bottle neck, to the interior of the guard.

A ball valve 14 is disposed within the neck 1 between the guard 5 and the valve seat 2, and is normally seatable upon the valve seat, 105 to close the passage through the neck, to thereby prevent the refilling of the bottle, but permitting the contents to be discharged without difficulty.

The tubular guard or protector 5 is sealed 110 or anchored within the bottle neck by means of cement or other plastic material 15

oured into the grooves or channels 3 and filling said grooves and their branches 4, the cement also flowing into the annular groove 12 of the guard 5, in order that when 5 the cement solidifies, the same will securely lock the guard 5 against both longitudinal and rotary movements.

The valve seat 2 and cement grooves 3 may be provided in the bottle neck, during 10 the process of manufacture of bottle, in a comparatively inexpensive and facile manner. In assembling the valve and its guard with the bottle neck, the valve is first inserted, after which the guard 5 is inserted 15 into the neck, so that the gasket 11 will snugly engage the interior of the neck. Then, the guard 5 is slid inwardly or downwardly to proper position, the gasket 11 closing the space or gap between the guard and 20 interior of the bottle neck, to prevent the cement from flowing or running therebeyond. Then, the cement may be poured into the upper ends of the grooves or channels 3, to fill the branches thereof, the cement 25 flowing from the said branches into the annular groove or channel 12 of the guard, whereby the guard is firmly anchored in the mouth of the bottle, as soon as the cement solidifies.

30 In practice, the valve and guard are not inserted into the neck until after the bottle has been filled, so that after the valve and guard have been applied in the neck, the subsequent filling or refilling of the bottle 35 is prevented. The contents of the bottle may be readily poured out or decanted, in the usual manner, the valve 14 unseating when the bottle is inverted or tilted properly, in order that the contents may flow into 40 the neck of the bottle, and thence through the slots or ports 13 into the tubular guard 5, which serves as a dispensing spout for the bottle. As soon as the bottle is up-

righted, the valve 14 will be reseated, as will be evident.

The guard 5 prevents tampering with the valve, inasmuch as wires, or other implements cannot be inserted through the guard, to successfully unseat the valve, should malicious persons attempt to refill the bottle.

The upper end of the guard or protector 5 may be closed normally, by a stopper, or other closure, whereby the passage through the guard or sleeve 5 may be closed under ordinary conditions, which is desirable.

The cement filling the coöperating or intersecting grooves of the guard and neck, will effectively lock the guard within the neck and furthermore, will close the space between the guard and the neck, above the 60 slots or ports 13. The cement 15 thus provides a key engaging the grooves of the neck and guard, for preventing the displacement or removal of the guard, and for sealing the gap or space between the guard and 65 neck.

Having thus described the invention, what is claimed as new is:—

In combination, a bottle neck, a tubular guard disposed therein, the bottle neck having diametrically opposite Y-shaped recesses whose trunks extend to the upper end of the bottle neck, the guard having an annular groove intersecting the branches of the said recesses, cement filling the said recesses and 75 groove, and a valve disposed within the bottle neck below the guard, the guard having ports below the said groove.

In testimony that I claim the foregoing as my own, I have hereto affixed my signature in the presence of two witnesses.

THOMAS SUMMERSON.
